UNITED STATES PATENT OFFICE.

WILLIAM B. HILL, OF TERRE HAUTE, INDIANA.

ATTACHMENT FOR ELECTRIC FANS.

1,142,708.

Specification of Letters Patent.

Patented June 8, 1915.

Application filed October 3, 1914. Serial No. 864,746.

To all whom it may concern:

Be it known that I, WILLIAM B. HILL, a citizen of the United States, residing at Terre Haute, in the county of Vigo and State of Indiana, have invented certain new and useful Improvements in Attachments for Electric Fans, of which the following is a specification.

The present invention relates to an advertising streamer adapted to be employed in connection with electric fans and has for its primary object to provide a device of this character which embodies novel features of construction whereby a series of advertising cards may be displayed in a most effective manner.

A further object of the invention is to provide a device of this character which is comparatively simple and inexpensive in its construction, which can be quickly applied to any electric fan, which admits of the advertising cards being readily changed as found desirable, and which does not interfere in any manner with the usual action of the fan.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of an advertising streamer constructed in accordance with the invention, showing the same as applied to an electric fan. Fig. 2 is a similar view showing a modification of the invention, the position of the parts when in operation being indicated by full lines, while the position assumed by the parts when the fan is not in operation is indicated partially by dotted lines. Fig. 3 is a similar view showing a still further modification in which fan members are provided at the extremity of the streamer, said fan members dropping into the dotted line position when the electric fan is not in operation. Fig. 4 is a front elevation of the electric fan with the streamer supporting bracket applied thereto, the streamer itself being removed. Fig. 5 is a sectional view of the streamer supporting bracket on the line 5—5 of Fig. 4, portions being broken away and shown

in section, and Fig. 6 is a longitudinal sectional view through one of the hingedly connected sections of the streamer.

Corresponding and like parts are referred to in the following description and indicated in all the views of the drawing by the same reference characters.

For the purpose of illustration the invention is shown as applied to an electric fan of the conventional construction, the numeral 1 designating the motor, 2 the fan, and 3 the wire cage within which the fan rotates. The supporting bracket for the streamer includes a block 4 having an opening therein to receive a pair of rods which are secured at their middle portions to the block, the ends of the rods forming diverging arms 5 which are deflected inwardly and have clamps 6 secured to the extremities thereof. The clamps are shown as formed with hinged jaws which are adapted to be brought into engagement with the wire cage 3 of the fan, said jaws being held in operative position by means of the bolts 7 and wing nuts 8 thereon. Projecting from the block 4 is a pair of hinge pintles 9 which serve to detachably engage corresponding hinge eyes upon the first section of the streamer.

In Fig. 1 of the drawing the streamer is shown as formed of three hingedly connected sections, the first section including a card 10, the second section including a card 11, and the third section including a card 12, each of the said cards having suitable advertising matter marked thereon. End bars 13 are applied to both ends of the cards 10 and 11 and to the inner end of the card 12. These end bars 13 are provided with cooperating sets of hinge pintles 14 and hinge eyes 15 which detachably engage each other as well as the hinge pintles 9 of the supporting bracket to form a detachable hinged connection between the several sections of the streamer as well as between the base of the streamer and the block 4 of the supporting bracket. When the electric fan is in operation the current of air produced thereby will cause the streamer to flutter in front of the fan, thereby causing each of the advertising cards to wave slightly or vibrate back and forth so as to attract attention thereto.

In order that the various advertising cards may be readily replaced by other cards bearing different advertisements, the end

bars 13 are preferably constructed so as to detachably engage the edges of the cards. For this purpose, as indicated by Fig. 5, the end bars 13 may have a channel formation 5 so as to receive the edges of the advertising cards between the flanges thereof, and suitable fastening members 16 may pass through the flanges of the channel members together with the intervening edges of the cards so 10 as to provide a firm connection between the members. It will thus be obvious that a new card bearing a different advertisement can be readily substituted for the old card.

In Fig. 2 is shown a modification in which 15 the adjacent end bars 13^a of the cards 10^a and 10^b are arranged on a bias or at an angle to the longitudinal axis of the streamer. When the fan is in operation the current of air directed thereby against the streamer 20 will overcome the action of gravity and cause the streamer to rise into a substantially horizontal position, as indicated by full lines, although when the fan is shut off, the action of gravity will cause the card 10^b to 25 swing downwardly into an out of the way position, as indicated by dotted lines. Otherwise the streamer shown by Fig. 2 is identical in construction with that shown by Fig. 1.

30 A further modification is shown by Fig. 3 in which 10^b and 11^b indicate a pair of advertising cards having end bars 13^b applied thereto, said end bars being provided as in the previous instances with the co-operating 35 hinge pintles 14^b and hinge eyes 15^b. Arranged at the end of the pennant is a pair of small fans 17 which are pivotally mounted upon the outer ends of arms 18, the inner ends of the said arms being formed with 40 hinge eyes 19 which detachably engage the hinge pintles 14^b of the end bar 13^b at the outer end of the advertising card 11^b. When the electric fan is not in operation the swinging arms 18 and small fans 17 will 45 drop downwardly into the position assumed by dotted lines, although when the fan is turned on the current of air therefrom will not only act as in the previous instances to produce a waving motion of the hingedly connected sections of the streamer, but will 50 also act upon the small fans 17 in such a manner as to rotate the same and swing the arms 18 into alinement with the streamer. The rotation of these small fans 17 will 55 serve as an additional means to attract attention to the advertising cards, and the entire pennant will be in motion as long as the electric fan is in operation. A most effective advertising device will thus be provided, since 60 an animated or moving display never fails to attract attention, and all of the advertising cards will be read by every observer.

Having thus described the invention, what

I claim as new and desire to secure by Letters Patent, is:—

1. An advertising attachment for electric fans including a supporting bracket adapted to be attached to the electric fan, and a streamer connected to the bracket member and formed of a series of hingedly connected 70 advertising cards.

2. An advertising attachment for electric fans including a bracket member adapted to be attached to the electric fan, a series of advertising cards, end bars detachably applied to the ends of the advertising cards, and co-operating hinge pintles and hinge eyes upon the bars and bracket member so that the several advertising cards can be hingedly connected to form a streamer and the base of 80 the streamer hingedly connected to the bracket member.

3. An advertising attachment for electric fans including a bracket member adapted to be attached to the fan, a series of advertising cards, end bars applied to the edges of the cards at the ends thereof, means for hingedly connecting the end bars together to assemble the series of advertising cards in a streamer, means for hingedly connecting the streamer to the bracket member, a swinging arm loosely connected to the end bar at the extremity of the streamer, and a fan member journaled upon the swinging arm.

4. An advertising attachment for electric fans including a block, diverging arms projecting from opposite ends of the block, clamp members at the extremities of the diverging arms for detachably engaging the wire cage of the electric fan, a hinge member carried by the block, an advertising streamer, and a complemental hinge member at the base of the advertising streamer for detachably engaging the hinge member of the block.

5. An advertising attachment for electric fans including a block having an opening therethrough, a pair of rods extending through the opening and having the intermediate portions thereof secured within the opening, opposite ends of the rods providing diverging arms, clamp members at the extremities of the diverging arms adapted to detachably engage the wire cage of the electric fan, hinge members projecting from the block, an advertising streamer, and complemental hinge members at the base of the advertising streamer for detachably engaging the before mentioned hinge members of the block.

In testimony whereof I affix my signature in presence of two witnesses.

WILLIAM B. HILL.
